AUTOMATIC PIPE GRAPPLE

Nicholai M. Erdahl, Edgerton, Wis., assignor to
Highway Trailer Company, Edgerton, Wis., a
corporation of Wisconsin

Application August 12, 1933, Serial No. 684,857

10 Claims. (Cl. 294—118)

This invention relates to grapples or tongs of the type especially adapted for use in connection with the handling of pipes, poles, etc. The main object of this invention is to provide an improved grapple which may be quickly and easily attached to or released from the pipe. Another object is to provide, in a device of this character, means adapted to be automatically actuated upon encounter with the pipe or pole for causing movement of the gripping elements into positive gripping relation with the pipe or pole. A further object is to provide a grapple of the above mentioned type with novel means for securing the jaws in open position after the pipe or pole has been released therefrom. A still further object is to provide an improved grapple having pivoted jaws on the tong arms with means for automatically latching the jaws in gripping relation substantially simultaneously with movement of the jaws to gripping position. The invention consists in certain elements and features of construction, in combination, as herein shown and described, and as indicated in the claims.

In the drawings:

Figure 1 is a front elevation of a grapple embodying the present invention, shown in operative position supporting a section of pipe.

Figure 2 is a view similar to Figure 1 showing the jaws in open position and the pipe about to be embraced thereby.

Figure 3 is a side elevation showing the jaws in releasing position.

Figure 4 is a vertical section taken as indicated at line, 4—4, on Figure 1.

Figure 5 is a bottom view taken substantially as indicated at line, 5—5, on Figure 1.

Figure 6 is a detail sectional view taken at line, 6—6, on Figure 2.

The grapple or tongs embodying the present invention pertains to that type of device particularly adapted for use in connection with the handling of pipes, poles, etc. Such a device may be used in connection with a tackle and boom that is stationary or mounted on a vehicle. A device of this type is particularly adapted for use in handling pipes in laying oil and gas lines under construction, either in the removal of same from trucks, cars, etc., or placement thereof in ditches, trenches, etc. The device may also be conveniently employed in handling of telephone poles in connection with the construction or dismantling of a telephone system.

Referring now in detail to the drawings, it will be seen that my improved grapple includes a pair of tong arms, 10, 11, which are pivotally connected

together by means of a bolt, 12. These tong arms which are preferably castings are each composed of a pair of spaced apart side plates, 10^a and 11^a, respectively. The upper end of each tong arm is pivotally connected by means of a bolt, 13, to an upwardly extending link, 14, which links, 14, 14, are of a modified U shape, engaging a supporting ring, 15, which may be understood to be connected to a suitable hoisting tackle. The lower ends of the U-shaped links, 14, are swaged together and engaged between the spaced apart sides forming the respective tong arms 10, 11, as may be seen in the drawings. The side plates, 10^a, composing the tong arm, 10, overlap the side plates, 11^a, at their pivotal connection, and the side plates, 11^a, are spaced apart at the pivotal connection by means of a spacer block, 12^a.

Pivotedly connected to the lower ends of the tong arms, 10 and 11, by means of bolts, 17, are two cooperating jaws, 18 and 19, each of which has an arcuate gripping portion, 18^a, 19^a, which is shaped to conform to the contour of the maximum size pipe or pole to be handled thereby—it being understood that the device is designed for use in connection with pipes, poles, etc., of a plurality of sizes. The inner surface of the arcuate sections, 18^a and 19^a, of said jaws are provided with a suitable lining, 20, to insure positive gripping when the jaws are brought into operative engagement with the pipe indicated at 21. This lining, 20, also serves to prevent damaging the pipes or poles in handling. As may be seen from the drawings, these jaws are each formed with a pair of spaced apart parallel ribs, 18^b and 19^b, and these jaws swing between the spaced apart side members of the tong arms. The upper part of the jaws are designed so that the mass of the jaw with respect to the pivot connection provided by the bolt, 17, acts as a counterweight tending to swing the jaws inwardly at their upper ends.

Secured to upper ends of the ribs, 18^b and 19^b, on the respective jaws are pins, 18^d and 19^d, and pivotally mounted on the pin, 18^d, intermediate the ribs, 18^b, and substantially central with respect to the side bars of the respective tong arms is a substantially horizontally extending latch member 22, whose end opposite the pivot is formed on the under side thereof with a plurality of notches indicated at 22^a and 22^b, which in certain positions of adjustment of the tong arms are adapted to register with and engage the pin, 19^d, for locking the jaws, 18 and 19, in operative engagement with a pipe, 21, of certain diameter, as may be seen in Figure 1 of the drawings. When handling a pipe of larger diameter the pin,

19^d, will engage in a notch, 22^b. The under side of the latch member leading to the notch, 22^a, as well as the surface extending from the notch, 22^a, toward the notch, 22^b, are formed as cams 5 so that when said cam surfaces are engaged by the pin, 19^d, as the jaws swing open, the latch will be raised about its pivot until one of said notches, 22^a or 22^b, align with and engage said pin. The extreme outer end of the latch member, 22, is formed with an eyelet, 22^c, to which is connected an operating element, herein shown as a flexible cable, 23, which extends upwardly and is suitably connected to a place adjacent the operator so that it may be pulled when desired 10 for permitting the tong arms to separate and release the jaws to pivot about their hinged connections provided by the bolts, 17, for releasing the pipe. Formed on the upper end of one of the side plates, 10^a, of the tong arm, 10, is an eyelet, 10^c, for guiding the flexible rope, 23. The under side of the latch, 22, adjacent the pivot connection is formed with an extension producing a slot, 22^d, which slot is adapted to receive and accommodate the pin, 19^d, for securing the 15 jaws in open position after the pipe has been released, as may be seen in Fig. 2 of the drawings.

To maintain the tong arms with the jaws, 18 and 19, in open position after the pipe or pole has been released therefrom, I provide a detent 20 which includes a dog, 26, pivotally connected at 27, intermediate the spaced apart ribs, 18^b, of the jaw, 18. The inner end of the dog is formed with a counterweight, 28, which normally tends to swing the dog in vertical direction about its 25 pivot, 27, and is positioned for encounter by the pipe, 21. The opposite end of said dog is formed with a transversely extending web portion, 29, which is adapted when the jaws are swung to open position, by discharge of the pipe, to register with and abut against stop shoulders, 10^e, formed on the inner surface of the side plates, 10^a, of the tong arm, 10, as seen in Figures 2 and 6 of the drawings.

The operation of my improved grapple is as 45 follows: When it is desired to release the pipe, 21, from the jaws, the grapple is lowered until the pipe, 21, rests upon the ground. Then the rope, 23, is pulled so as to release the notched portion, 22^a or 22^b, of the latch, 22, from engagement with the pin, 19^d, which releases the jaws, 18 and 19, for free pivotal movement about their hinge connection provided by the bolts, 17, on the tong arms. Then the grapple is raised which movement causes the lower ends of the jaws to 50 act camwise against the lower surface of the pipe, 21, and be forced outwardly and the upper ends of said jaws moved inwardly. The inward movement of the upper ends of said jaws brings the pin, 19^d, into engagement with the slot, 22^d. 55 After the pipe is released the dog, 26, under the influence of its counterweight, 28, moves to operative position, as seen in dotted lines in Figure 2, so that its web portion, 29, abuts against the stop shoulders, 10^e, on the tong arm, 10, and thus prevents return movement of the jaw, 18, and the counterweight, 28, assumes a position as seen in dotted lines in Figure 2, so as to insure being first engaged and actuated by the pipe 60 when the grapple is lowered thereover. Due to the pin, 19^d, engaging in the slot, 22^d, of the latch member, 22, the jaw, 19, is also held in open position as seen in Figure 2. It will be understood that when the pin, 19^d, of the jaw, 19, is disposed in the slot, 22^d, the weight of the latch, 65 22, due to the substantial leverage will tend to

frictionally maintain the jaws and the tongs fixed in open position. And if for some reason the jaw, 19, is not held securely due to the frictional contact of the latch, such as may result when the grapple is being raised and jostled about slightly, it will be manifest that the pin, 19^d, can only travel to the end of the slot, 22, which will serve to definitely limit the inward movement of the upper end of the jaws and the closing of the tong arms. It will be understood that the tong arms in open position with the jaws swung to the position in Figure 2 will always accommodate the maximum size pipe capable of being handled. 80 85

When it is desired to pick up a pipe or a pole the grapple is lowered, with the jaws held in the open position as above described, and is permitted to drop over the pipe as seen in Figure 2 of the drawings, and when the pipe contacts the end of the counterweight, 28, it will swing the dog, 26, about its pivot, 27, so as to dispose the flange, 29, out of abutting engagement with the shoulders, 10^e, of the tong arm, 10, and the continuous downward movement of the grapple will thus bring the upper ends of the jaws as indicated at 18^f and 19^f, into contact with the surface of the pipe, and thereby cause the jaws to swing about their pivots; the upper ends moving outwardly and the lower ends inwardly so as to embrace the pipe. During such movement the pin, 19^d, of the jaw, 19, travels outwardly along the cam formation on the under side of the latch, 22, until it registers with either the notch, 22^a or 22^b, of the latch member, and it will be understood that the weight of the latch member due to remoteness of its pivotal connection to the other jaw will be sufficient to cause the latch member to drop by gravity and engage the pin, 19^d, and thereby lock the jaws in fixed relation. The grapple may then be bodily raised carrying 100 105 110 115 the pipe with it.

It will be understood that when a pipe larger in diameter than that shown in Figure 1 of the drawings is to be handled by the grapple, the jaws will be separated slightly farther, causing 120 the tong arms to open slightly more, thus causing the pin, 19^d, to engage in the notch, 22^b, of the latch. It will be recognized that by virtue of this construction the tong arms move very little, the gripping or releasing action taking place 125 substantially entirely by the movement of the jaws.

If it happens that the cable or rope, 23, becomes snagged, due to inadvertence of the operator in holding onto it too long, the jaws, 18 and 19, may not be inter-engaged, but may swing freely so that their upper ends tend to swing inwardly and downwardly about their hinge connections. To prevent the jaws from being disposed in an inoperative position I provide stop 130 lugs indicated at 18^g, 19^g, which are positioned to engage the outer edges of the side plates of the tong arms, 10 and 11, respectively, thus limiting such movement of the jaws; such limited movement of the jaws will still permit proper engagement thereof when the grapple is lowered over the pipe preparatory to raising same. 135 140 145

Although I have shown and described a preferred embodiment of my invention, it will be understood that the construction and arrangement of the parts may be varied without departing from the spirit and scope thereof. I do not therefore, wish to be understood as limiting myself to the specific construction illustrated and described, excepting as limited by the claims. 150

I claim:

1. In a grapple for handling pipes, poles, or the like, a pair of tong arms pivotally connected together, a pair of cooperating jaws pivotally connected to the lower ends of said tong arms for engaging the pipe, pole or the like, and means for locking said jaws to each other in fixed relation when they are so engaged.
2. In the construction defined in claim 1, together with remote control means operable at will for releasing the locking means and in turn permitting the jaws to disengage the pipe, pole, or the like.
3. In a grapple for handling pipes, poles and the like, a pair of tong arms pivotally connected together, a pair of cooperating jaws pivotally connected to the lower ends of said arms and adapted to engage pipes, poles or objects of a plurality of different sizes, and means operable when the jaws have been brought into engagement with the object, for locking the jaws in one of a plurality of positions corresponding to the size of the object engaged, said means including a latch member hingedly connected at one end to the upper end of one of the jaws, the upper end of the other jaw having a cooperating feature engageable in one of a plurality of notches formed in said latch.
4. In a grapple for handling pipes, poles, or the like, a pair of tong arms pivotally connected together, a pair of cooperating jaws pivotally connected to the lower ends of said arms, said jaws being counterbalanced so that when free their upper ends tend to swing toward each other, and a latch hingedly connected at one end to the upper end of one of the jaws, the upper end of the other jaw having a feature adapted to engage in a notch formed in the latch for locking the jaws in fixed relation when they are brought into engagement with the pipe, pole, and the like; the upper ends of said jaws being forcibly moved toward each other, incident to the discharge of the pipe, pole, or the like, and the latch being provided with a feature cooperating with said feature on said second mentioned jaw, tending to maintain said jaws and tong arms in open position.
5. In the construction defined in claim 4, said tong arms each including a pair of spaced apart side members between which said jaws are pivoted, and the latch member freely movable.
6. In the construction defined in claim 4, a detent carried on one of the jaws for assisting in holding said jaws and tong arms in open position, said detent being movable into operative engagement with the adjacent tong arm when said jaw swings to open position, incident to the discharge of a pipe, pole, or the like. 80
7. In a grapple for handling pipes, poles, or the like, a pair of tong arms pivotally connected together, a pair of cooperating jaws pivotally connected to the lower ends of said arms, said jaws being counterbalanced so that when free their upper ends tend to swing toward each other, and a latch hingedly connected at one end to the upper end of one of the jaws, the upper end of the other jaw and said latch having cooperating features, engageable when the upper end of the jaws swing toward each other incident to discharge of a pipe, pole, or the like, for holding said jaws and tong arms in open position. 85
8. In the construction defined in claim 7, a detent on one of the jaws, including a pivoted dog, movable into abutting relation with a shoulder on the adjacent tong arm, when the jaws are free, for assisting in blocking the jaws and tong arms in open position. 90
9. In the construction defined in claim 7, a detent on one of the jaws, including a pivoted dog, movable into abutting relation with a shoulder on the adjacent tong arm, when the jaws are free, for assisting in blocking the jaws and tong arms in open position. 95
10. In the construction defined in claim 7, a detent on one of the jaws, including a pivoted dog, movable into abutting relation with a shoulder on the adjacent tong arm, when the jaws are free, for assisting in blocking the jaws and tong arms in open position, and a counterweight associated with the dog normally tending to move it to operative position. 100
11. In the construction defined in claim 7, a detent on one of the jaws, including a pivoted dog, movable into abutting relation with a shoulder on the adjacent tong arm, when the jaws are free, for assisting in blocking the jaws and tong arms in open position, said dog including a depending part, 110 adapted when said dog is in operative position, to be disposed for encounter by the pipe, pole, or the like, as the grapple is lowered thereover preparatory to raising, whereby such engagement of said depending part swings the dog to inoperative 115 position and permits encounter with said jaws for swinging them into operative engagement with said pipe, pole, or the like. 120
